UNITED STATES PATENT OFFICE.

GEORGE FOWLER, OF LIVERPOOL, ENGLAND.

SURGICAL TRUSS.

Application filed August 3, 1925. Serial No. 47,813.

To all whom it may concern:

Be it known that I, GEORGE FOWLER, a subject of the King of Great Britain, residing in Liverpool, in the county of Lancaster and Kingdom of England, have invented certain new and useful Improvements in Surgical Trusses, of which the following is a specification.

This invention relates to trusses for the treatment of hernia, and has for its object to provide a truss which embodies a new principle and conforms more closely to the mechanical adaptation of the human hand in its application to the control of inguinal hernia.

It is a well known fact that if the hand is placed on the patient, with the thumb on the inguinal ring, after the hernia has been reduced, and the fingers around the pelvis in a line following the position of a truss spring, the most difficult hernia is easily controlled. It has been my aim in designing my truss to produce a truss in which the pad is applied with the requisite pressure on the hernia in such a manner as to simulate the grip of the human hand. In my improved truss the pad is adapted to maintain itself always in the correct position and to exert a constant pressure in the correct direction on the hernia and yet is able to accommodate itself easily to the movements of the abdomen of the patient, thereby giving efficient control of the hernia while permitting that freedom of movement which is essential to comfort. Furthermore, in my truss the faults hitherto incidental to trusses, such as pressure around the pelvis, pressure and chafing on bony prominences, and side to side pressure, have been eliminated.

The important features of the truss according to my invention are that the pad has a hinged connection with the usual band or spring that encircles the body by a hinge having a double joint; and further, the spring pressure on the pad is not derived from the spring body band, as usual, but is produced by a separate and independent spring at the end of the band acting directly on the pad itself. Further features and objects of the invention will be hereinafter set forth,

The invention will be more particularly described with reference to the accompanying drawings, in which an example of construction of my improved truss is illustrated.

Figure 1 is a perspective view, on a reduced scale, of a complete single truss intended for the control of right side inguinal hernia.

Figure 2 shows the truss in the position of use.

Figure 3 is a front elevation, drawn to full size, of the pad-plate and the double-jointed hinge.

Figure 4 is a plan view of Fig. 3, but with the guard-plate or shield for the spring fixed to the pad-plate.

Figures 5 and 6 are respectively an elevation and plan of the compound spring used for applying pressure to the hernia-pad.

Figure 7 is a plan view showing the hernia-pad and its spring, assembled and mounted on the end of the spring body-band, and with the spring under compression as when in use.

Referring to these figures, the hernia-pad 1 is hinged to one end of the spring body-band 2 by a hinge having a double-joint, and comprising in the construction illustrated a pair of parallel links 3 and 4, connected together by the hinge-pins 5 and 6 riveted into the ends of the links. The pad is hinged to the outer hinge-pin 6 by a metal bar 7, pivotally connected to the pad-plate 8 on its inner side and bent round at one end to form a knuckle 9 embracing the pin 6. 10 is a plate or bar knuckle-jointed at its outer end on the inner hinge-pin 5, and pivotally connected by the screw-pin 11 to the spring body-band 2, so as to be vertically movable with respect to said band. This bar 10 has a pin and slot connection to the body band 2 by means of the curved slot 12 and set-screw 13, for the purpose of varying the adjustment of the pad when fitting the truss on the patient. This adjusting means is of a type well known in connection with trusses.

Spring pressure is applied to the hernia pad 1 preferably by means of a blade-

spring, such as 14, which is adapted to press at two different points on the outer side of the pad-plate 8, and is secured by the screw 11 through the bar 10 to the spring body-band 2 so as to be adjustable in a vertical plane parallel to that of the bar 10 but independently thereof. At its inner end the spring 14 has a curved slot 15 of the same radius as the slot in the bar 10, and the spring is locked in its adjusted position by the set-screw 13.

The spring 14 is a compound spring, in that it is fitted with a supplementary spring blade 14^a which is riveted or screwed at its outer end to the free end of the spring 14 and extends towards the neck of the pad. A spring so made will press against the pad at two points, so as to maintain the parallel action of the pad when in use and apply pressure at the neck as well as towards the centre of the pad. Figs. 5 and 6 show the form of the spring 14 that I prefer to use in its unstretched condition, and Fig. 7 shows the spring under compression when the truss is in use. The bearing points of the compound spring might be fitted with anti-friction rollers.

The spring and the double-jointed hinge connection of the pad to the body-band in conjunction constitute essential characteristics of my truss. Upon the spring depends responsibility for the effective retention of the rupture, and in this respect it represents the pressure exerted by the human hand between the thumb and fingers, whilst the double jointed link-hinge permits inward and outward movement of the pad whilst always maintaining it parallel to the body. It will be seen that the construction and arrangement of the spring is such that it may be adjusted to apply the pressure to various points of the pad. The spring is removable and replaceable by another spring of shorter or longer length, or stronger or weaker, according to requirements, so as to apply the pressure either centrally or towards the end of the pad, and it is also vertically adjustable towards the top or bottom of the pad, according to the individual requirements of the case. By this means various degrees of pressure may be applied and the points of application of the pressure varied to suit the needs of the patient.

The pad 1 which may be of any suitable form or material, is attached by stitching or in other suitable manner to a metal pad plate 8 pivotally connected by a rivet 16 to the hinge bar 7, and has a curved slot 17 in which engages a set-screw 18 screwed into the end of the bar 7. By these means the pad can be angularly adjusted to a certain extent when fitting to the patient in a plane parallel to the hinge bar, and such adjustment is independent of

the adjustment permitted by its hinged connection to the spring body-band.

To gain access to this adjustment, it is simply necessary in the construction shown to take off the guard plate or shield 19 which covers the outer face of the pad-plate 8 and the spring 14. This shield 19, it will be noted, is shown as fitted on to the pad-plate by key hole slots 20 engaging the screws 21, and is secured by the screws 22.

The band 2 that encircles the pelvis can be covered with any suitable material, and need not be so springy as usual, as it is to be noted that it is not intended to grip or compress tightly, its function being merely to provide means whereby the appliance may be held in position, and not to exert pressure for the purpose of retaining the rupture. The necessary pressure for this latter purpose, as already mentioned, given by means of a finely tempered spring working independently and at the end of the band as already described. It will thus be seen that the band can be treated as a separate entity, and so shaped to the patient that it conforms to his or her particular anatomical structure, and made to lie closely and comfortably round the pelvis without pressure on any part.

23 is the usual strap at the opposite end of the spring body-band in a single truss, which strap is secured by engaging one of its holes on the outer end of the screw 11.

By means of the double hinge and the spring the pad, when correctly fitted, applies a pressure to the hernia in a manner similar to the grip of the hand, and when movement of the abdomen takes place the pad moves correspondingly outwards and inwards while always maintaining itself parallel with the body by the links turning on the inner hinge as a centre. The hinge being double-acting in effect, takes the place of the two thumb joints of the hand. The pad is limited in its movement outwards by the pressure of the spring, but not inwards. By the action of the double hinge the pad is maintained in a parallel position to the inguinal ring, and gives to the wearer that freedom of movement which is so essential to comfort.

It will be noted that the end of the metal spring in the body band is bent inwards, as at 24, and extends over the knuckle of the inner hinge and abuts against the knuckle of the outer hinge joint. This is for the purpose of forming a stop to prevent the links flexing inwards to such an extent as to get on a dead centre, or nearly so, and thus preventing the free working of the double hinge in the desired manner.

If desired, a little play can be allowed in the hinge-joints, so as to permit a slight vertical rocking movement of the pad.

Although the invention has been described more particularly in connection with a single truss, it is, of course, equally applicable for double trusses, as will be well understood by those skilled in the art.

I declare that what I claim is:—

1. A surgical truss, comprising a body-band; a hernia pad; a double-jointed hinge by which said pad is hinged to the body-band in such manner as to permit inward and outward movement of the pad whilst always maintaining the pad parallel to the body; and a spring connected to the body-band for applying spring pressure to the rear of the said pad.

10 2. A surgical truss, comprising a spring body-band; a hernia-pad; a double-jointed hinge by which the said pad is hinged to the body-band; means for connecting the two hinge-joints together in such manner as to permit the outer hinge joint to which the pad is hinged to turn about the inner hinge-joint; means for limiting the inward movement of the outer hinge-joint; and a spring 20 connected to the body-band and adapted to apply pressure to the rear of the hernia-pad.

25 3. A surgical truss, comprising a spring body-band; a hernia pad; a pad-plate to which the said pad is attached; a double-jointed hinge comprising a pair of parallel links; means for hinging the pad-plate to the outer hinge-joint; a bar hinged to the other hinge-joint and pivotally connected to the spring body-band; means for adjusting the said bar in a vertical plane on the body-band; means for limiting the inward flexure of the parallel links on the inner hinge-joint; a blade-spring pivotally connected to the said body-band and adapted to apply 40 pressure to the rear of the hernia pad; and means for adjusting the blade-spring in a vertical plane on the body-band.

4. A surgical truss, comprising a spring body-band; a hernia-pad; a pad-plate to which the said pad is attached; a double-jointed hinge comprising a pair of parallel links; means for hinging the pad-plate to the outer hinge-joint; a bar hinged to the other hinge-joint and pivotally connected to the spring body-band; means for adjusting the said bar in a vertical plane on the body-band; means for limiting the inward flexure of the parallel links on the inner hinge-joint; a blade-spring pivotally connected to the body-band and adapted to apply pressure at two different points on the back of the pad-plate; and means for adjusting said blade-spring in a vertical plane on the body-band.

5. A surgical truss, comprising a spring body-band; a hernia-pad; a pad-plate to which said pad is attached; a double-jointed hinge comprising a pair of parallel links; a pair of hinge-pins connecting the said links together at their ends; means for re-

stricting the inward movement of said links; a hinge-bar knuckle-jointed on the outer hinge-pin and pivotally connected to the pad-plate; a pin-and-slot adjustment connection between said bar and the pad-plate 70

to enable the angular position of the pad-plate on said hinge-bar to be varied; a bar pivotally connected to the spring body-band and knuckle-jointed to the other hinge-pin; a pin-and-slot adjusting means for enabling 75 said bar to be adjusted in a vertical plane on the spring body-band; a blade-spring pivotally connected towards one end to said body-band and adapted to apply pressure at its other end to the rear of the pad-plate; and means for adjusting said spring to enable 80 its pressure to be applied at various points between the top and bottom of said pad-plate.

6. A surgical truss, comprising a spring body-band; a hernia-pad, a pad-plate to which said pad is attached; a double-jointed hinge comprising a pair of parallel links; a pair of hinge-pins connecting the said 85 links together at their ends; means for restricting the inward movement of said links; a hinge-bar knuckle-jointed on the outer hinge-pin and pivotally connected to the pad-plate; a pin-and-slot adjustment connection between said bar and the pad-plate 90

to enable the angular position of the pad-plate on said hinge-bar to be varied; a bar pivotally connected to the spring body-band and knuckle-jointed to the other hinge-pin; pin-and-slot adjusting means for enabling 95 said bar to be adjusted in a vertical plane on the spring body-band; a compound blade-spring pivotally connected towards one end to said body-band and adapted to apply 100 pressure at two different points on the rear of the pad-plate; and means for enabling the blade-spring to be adjusted in a vertical plane parallel to the said bar and body-band to enable the pressure of the compound spring to be applied 105 at various points between the top and bottom of the said pad-plate.

7. A surgical truss, comprising a spring body-band; a hernia-pad; a pad-plate to which said pad is attached; a double-jointed hinge comprising a pair of parallel links; a pair of hinge-pins connecting the said 110 links together at their ends; means for restricting the inward movement of said links; a hinge-bar knuckle-jointed on the outer hinge-pin and pivotally connected to the pad-plate; a pin-and-slot adjustment connection between said bar and the pad-plate 115 to enable the angular position of the pad-plate on said hinge-bar to be varied; a bar pivotally connected to the spring body-band and knuckle-jointed to the other hinge-pin; pin-and-slot adjusting means for enabling 120 said bar to be adjusted in a vertical plane on the spring body-band; a blade- 125

130

spring pivotally connected towards one end to said body-band and adapted to apply pressure at its other end to the rear of the pad-plate; a pin-and-slot connection between the end of the blade-spring and the body-band to enable the pressure of said spring to be applied at various points between the

top and bottom of said pad-plate; and a guard-plate for covering the spring and the back of the pad-plate. 10

In witness whereof, I have hereunto signed my name this 23 day of July, 1925.

GEORGE FOWLER.
